(57) CLAIM

The ornamental design for a multi-tiered V-neck maxi dress, as shown and described.

DESCRIPTION

FIG. 1 is a front view, in which dashed lines represent stitching; and,

FIG. 2 is a back view, in which dashed lines represent stitching.

The dashed lines representing stitching throughout the various views form no part of the claimed design.

1 Claim, 2 Drawing Sheets
